Primary Examiner — Cynthia Ramirez*Assistant Examiner* — Michael A Maharajh(74) Attorney, Agent, or Firm — Kile Park Reed & Houtteman PLLC(57) CLAIM

I claim the ornamental design for a skin care beauty device, as shown and described.

DESCRIPTION

FIG. 1 is a top and front perspective view of a skin care beauty device, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

1 Claim, 5 Drawing Sheets(56)
